United States Patent Office

Des. 189,034

Patented Oct. 18, 1960

189,034

TILE

Kenneth E. Froberg, Plymouth Meeting, Pa., assignor to American Encaustic Tiling Company, Lansdale, Pa., a corporation of New York

Filed June 16, 1959, Ser. No. 56,368

Term of patent 14 years

(Cl. D18—2)

I claim:

The ornamental design for a tile, substantially as shown.
